UNITED STATES PATENT OFFICE.

WILLIAM C. GLASS, OF BOSTON, MASSACHUSETTS, ASSIGNOR TO UNITED PRINTING MACHINERY COMPANY, OF BOSTON, MASSACHUSETTS, A CORPORATION OF MAINE.

SHEET-FEEDING MECHANISM.

1,135,175.

Specification of Letters Patent. Patented Apr. 13, 1915.

Application filed October 18, 1909. Serial No. 523,235.

To all whom it may concern:

Be it known that I, WILLIAM C. GLASS, of Boston, in the county of Suffolk and State of Massachusetts, have invented certain new and useful Improvements in Sheet-Feeding Mechanism, of which the following is a specification.

This invention relates to sheet feeding mechanism adapted to be used in connection with a reciprocatory press having a swinging press member. It is customary to provide for a press of this type a feed table from which the sheets may be fed, one by one, to the press couple. The press illustrated herewith has an upright chase, a swinging platen and a feed table arranged above the chase.

The object of the invention is to provide means for automatically transferring the sheets, one by one, from the feed table to the press and for removing the sheets from the press and for releasing them after removal from the press whereby they may drop into a receiving rack.

It is immaterial so far as the present invention is concerned whether the press is designed for printing or for cutting, but for the purpose of explanation, a press is herewith illustrated which is adapted to cut and score sheets of relatively thick paper or cardboard from which folding boxes are made.

Of the accompanying drawings, which illustrate one form in which the invention may be embodied,—Figure 1 represents a side elevation of a reciprocatory press, a feed table, a receiving rack and means for transferring the sheets from the feed table to the press and then to the receiving rack.

Fig. 2 represents a front elevation of the transferring mechanism. Fig. 3 represents a section on line 3—3 of Fig. 2. Fig. 4 represents a section on line 4—4 of Fig. 2. Fig. 5 represents a section on line 5—5 of Fig. 2.

Fig. 6 represents a transverse section of a part of the mechanism shown in Fig. 5. Fig. 7 represents a section on line 7—7 of Fig. 2. Fig. 8 represents a section on line 8—8 of Fig. 2. Fig. 9 represents a detail of the means for releasing the grippers. Fig. 9a represents a part of said means detached.

Fig. 10 represents a top plan view of the means for releasing the grippers. Fig. 11 represents a section on line 11—11 of Fig. 1.

Fig. 12 represents a side elevation of an adjustable connection at the other side of the machine, similar to that shown by Fig. 11. Fig. 13 represents a detail in section of a part of Fig. 12. Fig. 14 represents a side elevation of the feed table and actuating means therefor. Fig. 15 represents a vertical section of the means for actuating said table. Fig. 16 represents a front elevation of the feed table. Figs. 17 and 18 and 19 represent edge elevations of a pair of grippers and a sheet in different positions which it occupies when the grippers are in position to close upon the sheet. Fig. 20 represents a plan view of an adjustable stop. Fig. 21 represents a modified form of gripper jaw.

The same reference characters indicate the same parts wherever they occur.

Referring first to Fig. 1, a printing or cutting chase is indicated at 20 and the platen therefor is indicated at 21. The chase and platen constitute stationary and swinging members of a press couple and for the purpose of the present invention it is immaterial whether the chase is stationary and the platen is movable or vice versa. A fixed work support or table is indicated at 22 and the movable feed table is indicated at 23. The fixed table is intended to support a pile of sheets and the movable table is intended to receive the sheets, one by one, and hold them in position from which they are subsequently transferred to the press. The movable table is mounted upon a pair of arms 24 which are pivotally connected at 25 to the supports for the fixed table. The movable table is therefore adapted to rise and fall with relation to the fixed table. A receiving rack is indicated at 26 and is provided with stationary arms 27 which receive the sheets and guide them to the receiving rack. The swinging press member 21 is mounted upon a carriage 28 and it supports and carries the automatic mechanism which is operated to first transfer the sheet from the feed table to the press and to then remove the sheet from the press to a point of discharge over the arms 27 where the sheet is released so that it may drop into the receiving rack.

The means for so transferring the sheets comprises successive sets of grippers which revolve with relation to the swinging press.

member, said grippers being so actuated as to take a sheet from the feed table when the two press members are in co-operative position, to carry said sheet away from the feed table when the swinging press member is removed from the stationary press member, to place the sheet in operative position with relation to the swinging press member while the latter is again approaching the stationary press member and while a succeeding set of grippers is advancing toward the feed table, and to remove the sheet from the swinging press member and to discharge the same while the succeeding set of grippers is removing a sheet from the feed table. The sheet transferring mechanism herewith illustrated comprises three sets of grippers, which become active in turn. Each gripper, after discharging a sheet, remains idle during the succeeding stroke of the swinging press member. The press herein illustrated is a well-known construction and requires no detailed description. It may be stated, however, that the carriage 28 receives an oscillatory motion by which its angle is changed, and a rectilinear motion by which it is moved into engagement with the stationary press member. Motive power for the press is taken from a prime power shaft 29 which is provided with pinions 30 which drive gears 31 affixed near opposite ends of a crank shaft 32. The shaft 32 is provided with cranks 33 by which the swinging press member is reciprocated through the medium of connecting rods 34. The limits of movement of the swinging press member are shown by Fig. 1 in which open position is shown by solid lines and closed position is shown by dotted lines.

The feed table 23 is moved each time a set of grippers arrives at gripping position for the purpose of placing the edge of the sheet in engagement with the grippers so that the sheet will not be bent when the grippers close upon it. The means for effecting this movement of the feed table is shown by Figs. 14 and 15. A rock shaft 25 is mounted in bearings formed in the feed table frame and is provided with cams 36 which bear upon rolls 37. The rolls are mounted upon supporting rods 38 whose lower ends have screw-threaded connection with adjusting nuts 39. The nuts 39 are seated upon blocks 40 pivoted upon the supporting structure 41 of the fixed table 22. One of the cams 36 is provided with a spur gear segment 42 which intermeshes with a rack 43 at one end of a slide 44. The slide is provided with a stud 45 which occupies a slot 46 formed in the head of a rod 47. The rod is mounted so as to slide in a hanger 48 which is pivoted upon the same axis as the arms 24 which support the feed table. The head of the rod 47 is also pivotally connected to the free end of an arm 49 which is pivotally mounted at 50.

The arm 49 is connected by means of a link 51 to a bell-crank arm 52 mounted upon a pivot 53. The bell crank comprises two rigid arms 54 and 55 which are adapted to be engaged by a roll 56 carried by one of the gears 31 upon the crank shaft. The direction of rotation of the crank shaft is indicated by the arrow in Fig. 14, and the bell-crank arms 54 and 55 are so related that first one and then the other is engaged by the roll 56 and the bell crank is therefore rocked first in one direction and then the other. The rocking of the bell crank is transmitted in turn to the arm 49, then to the rod 47, then to the slide 44 and then to the cams 36 which are so formed as to rise and fall with relation to the rolls 37. It will be observed that the slot 46 is concentric with relation to the pivot 25 and it therefore follows that the rise and fall of the stud 45 does not cause any longitudinal movement of the slide.

The feed table is provided with front gages for a sheet and with guides for guiding the edge of the sheet to the front gages. The gages and guides are movable and are adapted to be retracted from the plane of the sheet immediately prior to removal of the sheet by the grippers hereinafter described. The movement of the gages and guides is effected by the rock shaft 25. The supporting frame for the feed table is provided with bearings for a stationary transverse rod 57 and a parallel rock shaft 58. Upon the rod and the rock shaft are mounted two sliding carriages 59, each of which is provided with a stud 60 upon which is pivotally mounted a gage block 61. The gage blocks are bifurcated and each embraces an arm 62 mounted upon the rock shaft 58. The arms are splined or otherwise connected to the rock shaft so as to be rocked thereby and to be longitudinally movable thereon. The gage blocks are provided with screw-threaded apertures which are occupied by the stems of front gages indicated at 63.

As shown by Fig. 16, each of the front gages is formed with a plurality of radial fingers either of which may be turned to operative position to be engaged by the front edge of a sheet. The gage blocks are also provided with spring followers 64 which abut against the gages and hold them against rotation. The gage blocks are provided with edge plates 65 which constitute continuations of the feed table for supporting the forward edge of the sheet in the plane of the table. The edge plates are cut away as indicated in Fig. 15 to receive the front gages 63. The free ends of the arms 62 are provided with guides 66 which guide the edge of the sheet toward the front gages and prevent the sheet from rising. The rock shaft 58 is provided with a gear segment 67 which intermeshes with a gear seg-

ment 68 affixed upon the rock shaft 35. When the rock shaft 35 is oscillated to effect a drop of the feed table, the segment 68 imparts oscillation to the segment 67 and the rock shaft 58 thereby swinging the guides 66 forwardly and downwardly out of the plane of the sheet. This movement of the guide arms 62 is transmitted to the gage blocks for the purpose of retracting the gages out of the path of the sheet.

As shown by Fig. 15, the arm 62 is formed with a cam slot 69, which is occupied by a stud 70 carried by an arm of the gage block. When the rock shaft 35 is turned in the opposite direction to elevate the table, the guide arms 62 are turned upwardly to the position shown and the front gages are restored to their operative positions. The carriages 59, together with the gages and guides 20 and edge plates are adapted to be adjusted transversely of the feed table by sliding them upon the rod 57 and rock shaft 58. In this way the gages and guides may be set for sheets of various widths. The forward end of the feed table is provided with a transverse groove 71, in which an adjustable side gage 72 is clamped.

In addition to the automatic rise and fall of the feed table, provision is made for securing a primary adjustment of the table. As shown by Fig. 15, the nuts 39 are provided with spiral teeth which intermesh with spiral gears 73 affixed upon a shaft 74. One end of the shaft 74 is provided with a handle 75 whereby it may be rotated to turn the nuts 39 and thereby raise or lower the supporting rods 38. When the height of the feed table is adjusted, its relation to the operating mechanism, shown by Fig. 14, is not disturbed because the segmental slot 46 is adapted to permit said movement and at the same time preserve its operative connection with the slide 44.

Fig. 1 shows a weight 76 suspended by a chain 77 which passes over a roll 78 and is attached to the feed table for the purpose of counterbalancing to some extent the weight of the table.

Referring now to the gripper mechanism, Fig. 2 illustrates one form in which there are two pairs of grippers for carrying a sheet. The grippers are supported by rotary carriers and the carriers are in turn supported by rolling trucks which are movable toward and from the platen and which are supported by side rods or bars 79, affixed to the platen. The structure of the carriage is shown by Fig. 3, in which a truck is indicated at 80 and is provided with grooved rolls 81 which embrace opposite sides of the bar 79. There are two such trucks, one on each bar, and they are so connected as to be movable in unison and, considered collectively, they constitute the carriage on which the gripper mechanism is mounted. The

swinging motion of the platen toward and from the chase is employed for effecting reciprocatory motion of the gripper carriage toward and from the platen. For this purpose, each of the trucks 80 is pivotally connected to a connecting rod 82, and the connecting rods are pivoted at 83 to adjustable studs by which the range of movement of the carriage may be increased or decreased. The details of construction of the adjustable pivots are shown in Figs. 11, 12 and 13.

The lower end of each connecting rod is provided with a yoke 84 which is adapted to slide upon a swivel block 85. The block is mounted upon a stud 83. The stud has 80 threaded connection with an adjusting screw 86 which is rotatably mounted in a bracket 87. The stud 83 is surrounded by a block 88 which is adapted to slide in a curved guide 89 formed in the bracket 87. The 85 curvature of the guide is concentric with relation to the pivots on the trucks 80 when the trucks are in the position shown by Figs. 1 and 12. The studs 83 are, however, adapted to draw the gripper carriage toward the 90 platen when the platen is drawn toward the carriage and to move the carriage away from the platen when the platen is moved away from the chase. The remote position of the carriage is invariable but by reason of 95 adjusting the pivot studs 83, the range of movement of the carriage may be increased or decreased. The adjusting rods 86 are provided with spiral gears 90 which intermesh with spiral gears 91 fixed upon a transverse shaft 92. One end of the shaft is provided with a crank 93 by which the adjusting screws 86 may be manually turned in unison to adjust both pivots 83 simultaneously.

As shown in Fig. 13, the connection between the connecting rod and the stud 83 is positive for the purpose of moving the carriage to its remote position but is yielding for providing lost motion for a purpose hereinafter explained. In Fig. 13 a spring is indicated at 94 by which the connection with the stud 83 is cushioned.

The two trucks of the gripper carriage are connected by a shaft 95. This shaft 115 does not revolve with relation to the trucks but is fixed thereto and is provided with two pairs of cams indicated at 96 and 97. There are two spiders 98, loosely mounted upon the shaft, each spider being arranged between a cam 96 and a cam 97 as shown in Fig. 6. The spiders are driven by gearing hereinafter described by which they are caused to revolve about the shaft 95. Each spider is formed as shown by Fig. 5 and 120 comprises three equally spaced arms in each of which is a radial slot 99. Each slot is occupied by a sliding block 100 which has a pivot stud 101 for a lever 102. The levers 102 are arranged and operate in pairs and 125 130

each pair is connected by a rigid rod 103 and a rock shaft 104. These levers are provided with cam rolls 106 which occupy grooves in the cams 96 and the sliding blocks 100 are provided with rolls 107 which occupy cam grooves in the cams 97. When the spiders 98 are rotated with relation to the cams, the blocks 100 are moved back and forth in the slots 99 and the levers 102 are oscillated about their pivots 101.

The gearing by which the spiders are driven is illustrated by Fig. 3 and is designed to effect rotation of the spiders when the platen is moved away from the chase but to leave the spiders stationary when the platen is approaching the chase. For this purpose each of the side bars 79 is provided with a gear rack 108. A gear 109 mounted upon the truck 80 remains in intermeshed relation with the rack at all times. A pinion 110 is affixed to the gear 109 and intermeshes with the gear 111 which is loosely mounted upon a bearing on a cam holder 96'. The gear 111 carries a pawl 112 which is adapted to coöperate with a ratchet disk 113, having three equidistant notches 114. The ratchet disk is affixed to the hub or sleeve 115 of the adjacent spider 98. The cam 96 is provided with a retaining pawl 116 which also coöperates with the notches 114. It is apparent that gearing of this character is adapted to drive the ratchet 113 and consequently the spider intermittently in one direction and that the ratchet is held rigidly by its retaining pawl when the driving pawl is returning to engage the succeeding notch.

The rods 103 and rock shafts 104 which are carried bodily about the central shaft 95 are provided with gripper jaws indicated respectively at 117 and 118. There may be two or more pairs of gripper jaws mounted upon each rod and rock shaft, the gripper jaws 117 being stationary with relation to the rod and rock shaft and the gripper jaws 118 being splined upon the rock shaft and adapted to turn therewith. Springs 119 are provided for normally closing the grippers and the grippers are otherwise opened against the tension of the springs.

Each of the rock shafts 104 is provided with an arm 120, each arm having at its free end a roll 121 adapted to coöperate with a stationary cam 122 affixed upon the central shaft 95. The cam has a pivoted section 123 mounted at 124, and provided with a segmental slot 125 which is occupied by a clamping stud 126 on the main body of the cam. The movable section is adapted to be placed at various positions for timing the opening of the grippers. The cam is provided with another movable section 127 which is for the purpose of effecting the release of the arms 120 and which thereby times the closing of the grippers. The sec-

tion 127 is loosely mounted upon the central shaft 95 and is connected to the spring 128 which normally holds it against a stop 129. This section of the cam may be affixed upon the shaft 95 and is adapted to be engaged by adjustable blocks 130 carried at the free ends of the cam arms 120. The ends of the blocks 130 are substantially square and the extremity of the section 127 terminates abruptly and it therefore follows that when the blocks 130 leave the extremity of the section 127, as shown by Fig. 9, the release of the cam arms 120 is sudden and complete as distinguished from a rolling contact which would result if the rolls 121 were utilized for the purpose of holding the grippers open after having once opened them.

The order of operation of one of the cam arms 120 is as follows: The arms are carried in the direction of the arrows in Fig. 8, and when the roll of the lowest cam arm engages the movable cam section 123, said cam arm is moved to open its grippers. The roll 121, after engaging the section 123, continues to roll upon the main part of the cam 122 until the block 130 engages the movable cam section 127, whereupon the tension of the arm 120 is transferred to the block 130 and the section 127.

The section 127 is retracted against the tension of the spring 128 by means for timing the release of the arms 120. As shown by Figs. 9, 9^a and 10, the hub of the section 127 is provided with a frusto-conical stud 131. The stud is adapted to be engaged by a head 132 formed upon one end of a feather 133 inserted in a longitudinal groove in the central shaft 95. The outer end of the feather (see Fig. 2) is provided with another head in which is a slot 134. The slot is occupied by a pin 135 carried by an arm 136. The arm is affixed at one end of a rock-stud 137 mounted in a bearing 138 on the truck 80 (see Fig. 12). The other end of the rock stud has a finger 139 which is formed with a spherical head occupying a groove 140 in the head 141 of a rod 142. The head 141 is formed with a slot 143 and it is adapted to slide upon the stud 144 by which the connecting rod 82 is connected to the truck 80. The rod 140 extends parallel to the connecting rod 82 and is connected at its lower end to an abutment such as the pivot 83 to which the rod 82 is also connected. The rod 82 is adapted to yield in one direction as previously explained but the rod 142 is not so adapted to yield.

When the platen carriage is moved to the position indicated by dotted lines in Fig. 1, the trucks 80 engage stops 147 and move the connecting rods 82 slightly away from the lower pivots 83 and the lower ends of the connecting rods therefore move longitudinally with relation to their pivots. The rod 142, however, is not adapted to move with 130

relation to the pivot 83 and the carriage trucks 80 therefore move with relation to the upper end of the rod 142. The relative movement thus effected is transmitted to the rock stud 137 and in turn to the feather 133 which is drawn outwardly so as to move the head 132 into engagement with the conical stud 131 and retract the section 127.

The grippers are adapted to be moved 10 transversely of the machine in order to enable them to carry sheets of various widths. They may be slid upon the rods 103 and rock shafts 104 to the desired positions where they may be secured by the clamping 15 screws 145. The jaws of the grippers are sufficiently long to be resilient and each pair of grippers is therefore adapted to grip the sheet with tension independent of the tension of the other grippers. The grippers 20 117 may be provided with teeth or pointed studs 146. As shown by Figs. 17, 18 and 19, the jaws of the grippers are so formed as to close upon the edge of a sheet without bending the sheet and they are therefore 25 adapted to close without disarranging the sheet.

The stops 147 are mounted on the side bars 79 in position to be engaged by the trucks 80 for the purpose of limiting the movement 30 of the carriage toward the platen. By this means, the grippers may be caused to register at any desired position with relation to the platen for the purpose of holding the sheet in the operative position. One of said 35 stops is shown by Fig. 1 and comprises a block adapted to slide on the side bar. The block is provided with a spring pawl 148 which co-operates with a rack or ratchet 149 formed in the bar 79. The stops may be 40 provided with gear racks 150 and a transverse shaft having pinions 152 may be provided for moving the racks 150. By means of a hand wheel 153 on the shaft 151 the stops may be simultaneously adjusted to the 45 same degree.

When the press is in the position shown by Fig. 1, one set of grippers is in position to feed the sheet to the platen. The upper set of grippers is ready to move to the 50 feed table to take the sheet therefrom and the third set of grippers is idle after having been opened to release a sheet. When the platen is moved toward the chase, the gripper carriage moves upon the side bars 55 toward the platen. But before the platen engages the form in the chase, the trucks 80 engage the stops 147 and thereby register one set of grippers with relation to the platen. The succeeding set of grippers, 60 meanwhile, move to the position shown by Fig. 17, and the feed table is then permitted to drop. The front edge of the sheet is thereby placed in engagement with the lower grippers, as shown by Fig. 2, and the 65 front gages and sheet guides are soon after

retracted from the path of the sheet. A slight continued movement of the platen after the carriage trucks are arrested by the stops 147 effects the retraction of the releasing cam 127. The grippers at the feed 70 table are therefore released and permitted to close to the position shown by Fig. 19, and in so closing they preserve the edge of the sheet in the same plane as the rest of the sheet.

When the platen is moved back to its open position, the trucks 80 are moved toward the outer ends of the side bars 79 and the spiders 98 are revolved. The grippers leaving the feed table are then rotated about 75 the central shaft 95 so as to place the new sheet upon the platen. The grippers, previously co-operating with the platen, are retracted for the purpose of removing the sheet from the platen. The movement of 80 these grippers is, however, not a rotary movement but, on the other hand, is a rectilinear one and is caused by the straight portion of the cams 96 and the irregular portions of the cams 97. The sheets are, 85 therefore, moved edgewise when being removed from the platen, instead of being rocked upon the upper edge thereof. When, however, the sheet is drawn sufficiently beyond the upper edge of the platen, the 90 grippers by which it is carried are moved in a curved path and are then opened by the cam section 123 whereupon the sheet is released and permitted to discharge into the receiving rack 26.

The movements of the several sets of grippers as effected by the cams 96 and 97 is a differential movement, not only in regard to the path of the grippers but in regard to the speed. While one set of grippers is 100 moving rotatively from the feed table, another set of grippers is moving in a rectilinear path to withdraw a sheet edgewise from the press.

The feed table is immediately raised to its 105 former position after a sheet is removed therefrom. It is apparent that the movement of the gripper carriage toward the platen may be quickly determined by adjusting the stops 147. After having determined the length of travel of the carriage, it is necessary to adjust the pivots 83 to give the required travel and to provide for the excess motion by which the release of the open grippers is effected. After this has 110 been done, the adjustment of the feed table remains for the purpose of positioning the forward edge of the sheet with relation to the grippers. These three adjustments may be procured without appreciable loss of time 115 by simply turning the cranks 75 and 93 and the hand wheel 153. It is apparent also that the adjustment of the various parts to various positions does not disarrange the 120 operating mechanism and that the feeder 125 130

may be quickly changed to handle sheets of different sizes.

In practice, a platform 154 may be provided for the attendant to stand on for the purpose of removing the sheets, one by one, from the pile on the table 22 and placing them upon the feed table. A brake lever 155 pivoted at 156 and having a shoe 157 may be provided for engaging a wheel 158 affixed upon the prime power shaft 29. The lever 155 may be provided with a treadle rod 159 and a treadle 160 where the attendant may depress it without leaving the platform.

15 The form of gripper shown by Fig. 21 may be used when it is desired to grip the middle of a relatively wide sheet in addition to the other grippers shown. In this form a gripper jaw 118 is affixed upon the cam arm 120 and a jaw 117 is affixed upon a block 117 supported by the rod 103 and rock shaft 104.

Having thus explained the nature of my said invention and described a way of constructing and using the same, although without attempting to set forth all of the forms in which it may be made or all of the modes of its use, I declare that what I claim is:-

30 1. The combination with a press and feed table, of means carried by the movable press member for taking a sheet from the table and holding it in the press, a pivot, and means connecting said pivot and said sheet-carrying means for moving the latter relatively to the movable press member for the purpose specified, said pivot being adjustable for varying the carrying movement of said carrying means.

40 2. The combination with a press and feed table, of means carried by the movable press member for taking a sheet from the table and holding it in the press; operating means including a stationary pivot and means connecting said pivot and said carrying means for moving the latter relatively to the movable press member for the purpose specified; said pivot being adjustable for varying the carrying movement of said carrying means, and an adjustable stop for limiting the movement of said carrying means toward the press to determine the operative position of the sheet in the press, said operating means having yielding 50 vision for enabling said sheet-carrying means to continue moving with the movable press member when the carrying means is against said adjustable stop.

3. The combination with a press having a swinging press member, of grippers carried by said member, said grippers being rotated with relation to said member and movable toward and from said member, yielding means for reciprocating the grippers 60 toward and from said member, and adjust-

able stops carried by said member for limiting and varying the movement of the grippers toward said member.

4. The combination with a press having a swinging press member and a feed table, of 70 successively operative sets of grippers carried by said member whereby one set is movable toward and from said member while a succeeding set is movable toward and from the feed table, means for effecting the closing of the grippers at said feed table, and means for positioning each successive set of grippers with relation to said member, said means also serving to time the closing of each successive set of grippers at the feed 75 table.

5. The combination with a press having a swinging press member, of rotatable carriers supported by said press member, grippers movably mounted in said carriers, means for 80 rotating the carriers, and means for moving the gripper relatively to the carriers to cause the grippers to turn in a non-circular path about the axis of the carriers.

6. The combination with a reciprocatory 90 press, and work table, of a carrier movable with the reciprocatory member of the press couple, grippers on said carrier for transferring a sheet from the table to the press, and means for opening the grippers to discharge 95 a sheet and holding them open continuously thereafter until they are in position to grip a sheet on the feed table.

7. The combination with a reciprocatory press, and work table, of a carrier movable 100 with the reciprocatory member of the press couple, and grippers on said carrier for transferring a sheet from the table to the press, said grippers having work engaging faces whose planes are in the plane of the 105 feed table when in gripping position.

8. The combination with a press having a swinging press member of a movable feed table, retractable stop gages for positioning the front edge of a sheet on the table, grippers carried by said movable member for transferring a sheet from the table to the press, means for effecting a movement of the table to place the sheet against a face of the grippers, and means actuated by said 110 table-moving means for retracting said gages below the table.

9. The combination, with a press having a feed table, of grippers for transferring a sheet from the table to the press, means for 115 holding the grippers open, a fixed abutment, and means permanently connected to said abutment and said holding means for moving the holding means to release the grippers.

10. The combination with a press having a feed table, of grippers for transferring a sheet from said table to the press, a carriage for said grippers, means for holding 120 the grippers open, a fixed abutment, and 125

means connected to said abutment for moving said carriage and for moving said holding means to release the grippers.

11. The combination with a press and feed table, of means carried by the movable member of the press for taking a sheet from the table and holding it in the press, said means being movable toward and from said movable press member, a fixture, yielding means connecting said sheet-carrying means and said fixture for moving said carrying means relatively to said movable press member in consequence of movement of the latter, a stop for positioning said sheet-carrying means relatively to the press to determine the operative position of the sheet in the press, said sheet-carrying means including a series of sets of grippers disposed so that one set co-operates with said table when another set is holding a sheet in the press, movable means for holding said grippers open, springs for closing the grippers, and means operative in consequence of further closing movement of said movable press member after said sheet-carrying means is against said stop, for moving said gripper-holding means to release the grippers which are in co-operative relation to the feed table.

12. The combination with a movable press member, of sheet-gripping means carried by said press member and arranged to be movable relatively to the latter, a stationary pivot, and a link connecting said pivot and said sheet-gripping means and arranged to cause sheet-carrying movement of the latter relatively to said press member in consequence of movement of said press member.

13. The combination with a press of a movable feed table, movable front gages and movable work guides for a sheet on the table, and means for effecting a movement of the table to place a sheet in engagement with the grippers, means actuated by said table-moving means for moving the gages and guides away from sheet engaging position, said means being adjustable for adjusting the table and adapted to preserve its operative relation during change of adjustment.

14. The combination with a press having a reciprocatory press member, of a carriage movable with said member, and movable toward and from said member, grippers movably mounted on the carriage, and cams movable with said carriage for actuating the grippers.

15. The combination with a press having a reciprocatory press member, of successive sets of grippers movable with said member and movable toward and from said member, means for effecting movement of the grippers toward and from said member, said moving means being adjustable for varying the movement of the grippers, means for positioning said grippers with relation to said member, and means for co-operating

with said positioning means for timing the closing of one of said sets of grippers.

16. The combination with a press having a swinging press member, of grippers carried by said member, a feed table, said grippers being movable toward and from said feed table, spring-tensioned means for closing said grippers, controlling means for holding open and releasing said grippers, yielding means for imparting bodily carrying movement to said grippers, and means for arresting movement of said grippers relatively to the press member by which they are carried, and for effecting actuation of said controlling means to release said grippers.

17. The combination with a press having a swinging press member, of a series of sets of grippers carried by said member, a feed table, said grippers being movable toward and from said press member and feed table, and otherwise movable so as to cause said sets to occupy operative position in turn with relation to the press and feed table, spring-tension means for closing said grippers, controlling means for holding open and releasing said grippers, means for causing bodily carrying movement of said grippers toward and from said feed table and press member, said controlling means being adapted to be caused to release said sets of grippers in turn, and means for arresting movement in one direction of said grippers, whereby one set of grippers is positioned with relation to said press member, and whereby said controlling means is operated to release another set of grippers.

18. The combination with a press having a swinging press member, of grippers carried by said press member, said grippers being movable toward and from said press member, and rotatively movable, and arranged in sets, the sets being arranged in an endless series whereby rotation causes the sets to move successively into operative relation with the press member, means for reciprocating the grippers toward and from the press member, means for rotating the grippers step by step to place them in turn in operative relation, spring-tension means for closing the grippers, controlling means for holding open the grippers and releasing the sets in turn, said controlling means being adapted to be operated by relative movement of said reciprocating means and the grippers, and means for determining the length of reciprocative movement of the grippers whereby one set of grippers is positioned with relation to the press member, and another set of grippers is released.

19. The combination with a press having a swinging press member, of grippers movable with said press member, and movable toward and from said press member, and otherwise movable in an endless path, said

2. grippers being divided into sets arranged in an endless series, and means for moving the grippers toward and from the press member, and otherwise moving them in their 5 endless path to cause one set of grippers to travel in the plane of said press member and at the same time to cause a succeeding set to move toward said plane.
20. The combination with a press having 10 a swinging press member, of a feed table, grippers movable with said press member toward and from said feed table, and movable toward and from said member, said grippers being movable about a common axis 15 and divided into sets arranged in an endless series whereby said sets, turning about said axis, move successively into operative relation first with said feed table and then with said press member, and means for causing 20 differential movement of said sets of grippers about said axis.
21. The combination with a press having 25 a swinging press member, of a feed table, grippers divided into sets, said sets being arranged in an endless series, said grippers being movable about an axis whereby each set in turn may occupy operative relation first with said feed table and then with said press member, the grippers being movable 30 toward and from the press member to insert a sheet in the press and remove it, and movable with the press member to take sheets one by one from the feed table, and means for causing the several sets of grippers to 35 describe differential movements about said axis, whereby the set carrying a sheet from the feed table is caused to turn about said axis, and at the same time another set is caused to remove a sheet from the press in 40 the plane of the swinging press member.
22. The combination with a press having 45 a reciprocating press member and a feed table, of grippers mounted on said press member so as to reciprocate therewith to and from the feed table, said feed table being arranged to support a sheet in position to be gripped, and the gripping faces of said grippers being arranged to lie in the plane of the table when gripping a sheet thereon, 50 and means for moving the grippers to convey the sheet from the feed table and hold it during the operation of the press.
23. The combination with a press, of a feed table, grippers for transferring a sheet 55 from the feed table to the press, front guides for the sheet on the table, said guides being mounted to move downwardly from sheet-engaging position to a plane below the table, front gages adapted to move downwardly 60 from sheet-engaging position to a plane below the table, said guides and gages being movable about different axes, and means for moving said guides and gages downwardly from sheet-engaging position while the grippers are in gripping position.
24. The combination with a press, of a feed table, grippers for transferring a sheet from the table to the press, means for moving the table to place the sheet against the grippers, front gages for the sheet, and 70 means actuated by said table-moving means for retracting said gages from sheet-engaging position.
25. The combination with a press, of a feed table, grippers for transferring a sheet 75 from the table to the press, means for moving the table to place the sheet against the grippers, front gages for the sheet, front guides, and means actuated by said table-moving means for retracting said gages and 80 guides from sheet-engaging position.
26. The combination with a press, of a feed table, grippers for transferring a sheet, from the table to the press, movable front guides for a sheet on the table, movable 85 front gages for said sheet, said guides and gages being movable in different directions from sheet-engaging position to positions below the plane of the table, means for reciprocating one of said sheet-engaging elements to and from sheet-engaging position, and means for transmitting movement from the element so reciprocated to the other of said sheet-engaging elements to retract said other element from sheet-engaging position. 90
27. The combination with a press, of a movable feed table, grippers for transferring a sheet from the table to the press, an adjustable support, actuating means engaging said support for moving said table to 100 place a sheet in engagement with the grippers, and operating means for said actuating means, said operating means and said actuating means being connected so as to preserve their operative relation when said support is adjusted to vary the arrangement of the table.
28. The combination with a press, of a movable feed table, grippers for transferring a sheet from the table to the press, a reciprocatory actuator having a fixed path of movement, means movable with said table for effecting movement of the table to place a sheet thereon in engagement with the grippers, and means connecting said actuator 115 and said table-moving means for operating the latter means, said connecting means preserving operative connection when the table is moving and in various positions.
29. The combination with a press and 120 feed table, of a rotatable support movable toward and from the press and toward and from the table, pivot members arranged in said support in an endless series about the axis thereof, a pair of complementary gripping members arranged on each point, means for turning the support about its axis, means for moving the support toward and from the feed table and toward and from the press, and means for causing differential 125 130

oscillation of the several pairs of grippers about their respective pivots.

30. The combination with a press and feed table, of grippers movable toward and from the table to take sheets therefrom, and movable toward and from the press to place the sheets therein, said grippers being arranged to turn about a common axis to place the sheets in the plane of the press, and 5 divided into sets, the sets being arranged in an endless series about said axis whereby they are adapted to be operated in turn, means for moving the grippers to and from the table, means for moving them to and 10 from the press, and means for causing differential rotative movement of the several sets of grippers about said axis.

31. The combination with a press and feed table, of grippers movable toward and from the table to take sheets therefrom, and movable to and from the press to place the sheets therein, said grippers being divided into sets, and each set comprising one or 20 more pairs of complemental gripping members, an individual pivot member for each pair of gripping members, said pivot members being movable about a common axis and movable toward and from said axis.

32. The combination with a press and

feed table; of grippers mounted on the movable member of the press, and movable relatively to said movable member for carrying a sheet from the feed table into the press, stationary adjustable means and connections therefrom to said grippers whereby carrying movement is imparted to the grippers when the movable press member is moved, and means for adjusting said stationary means to vary the carrying movement of the grippers.

33. The combination with a press frame, coöoperative press members mounted thereon, and a feed table; of grippers mounted on the movable member of the press couple, and movable relatively thereto for carrying a sheet from the feed table into the press, connections between said grippers and the press frame for imparting carrying movement to the grippers when the movable press member is moved, and means for adjusting said connections to vary the carrying movement of the grippers.

In testimony whereof I have affixed my signature, in presence of two witnesses.

WILLIAM C. GLASS.
